TREATMENT OF THREAD WITH LIQUIDS

Desiré C. F. Devos, Birdingbury, England, assignor to Courtaulds Limited, London, England, a British company

Application April 3, 1944, Serial No. 529,384
In Great Britain May 27, 1943

4 Claims. (CL. 8—155.1)

This invention relates to methods and apparatus for the washing and other wet treatment of coils of threads, as for example cakes of artificial thread such as are obtained by the centrifugal process. When such a cake is taken from the spinning box and treated with water, the thread swells and there is consequently a great tendency for creases or folds to form at many places within the cakes, such creases or folds generally running diagonally or in zig-zag directions and often extending some distance through the body of the cake. Such creases or folds are disadvantageous since they cause difficulties in the subsequent winding of the cake on to bobbins, pins or cones.

British specification No. 226,808 describes a method of treating coils or cakes of artificial silk which comprises transferring the cake to a portable carrier adapted to engage the cake at its inner periphery, detachably mounting the carrier upon a spindle, rapidly rotating the spindle and carrier, and supplying liquid to the cake at its inner periphery while the cake is rapidly rotating whereby liquid is caused to permeate the mass and be freely discharged from the outer periphery thereof by centrifugal action; it is also disclosed that the inner face of the cake may be protected by a perforated, reticulated or other suitable screen. British specification No. 362,114 describes a perforated resilient holder for the cake which is slightly concave and which may be made of for example hard aluminium alloy. British specification No. 365,810 describes an insert which consists of a flexible strip of permeable deformable absorbent paper or cloth. British specification No. 384,706 describes the use of a sleeve of thin permeable material such as cambric. The known types of inserts however have not been effective in preventing the formation of creases or folds on the inner layer of the cake.

I have now found that I can diminish or prevent the formation of these creases or folds hereinafter referred to as creases by inserting in the cake, before treatment with water or other aqueous liquid, a soft flexible and permeable sheath of elastic material, such as rubber, which sheath offers substantial resistance to the passage of the liquid and then forcing the liquid at a suitable pressure into the interior of the sheath through which it passes to the cake, thus exercising its washing or other treatment.

The process is of particular use when several cakes are placed on a central core in the manner described, for example, in the specification of British Letters Patent No. 349,681 or 483,856.

The cores in such cases are employed with an external diameter which is somewhat less than the internal diameter of the cake, since if the cakes fitted tightly on the core before treatment, their removal from the core after treatment would be difficult or impossible without damaging the cake. When carrying out the process of this invention with a plurality of cakes on one holder, it is preferred that the holder should be in a horizontal position during the treatment with liquid; the invention however is not restricted to such an arrangement since if desired the holder may be placed in a vertical or other position. The permeable sheath may consist of thin perforated rubber and the number and size of the perforations will be small compared with the number and size of the perforations in the holder.

When carrying out the process according to this invention the perforated sheath, since it offers substantial resistance to the passage of the water or other aqueous liquid, is forced and maintained against the inside of the cake or cakes and supports them evenly, and as the sheath is also elastic it readily maintains its direct contact with the cakes during any volume change which may occur during the liquid treatment, thus preventing or tending to prevent the formation of creases and giving a cake of even permeability. As indicated above, in order to effect the object of the invention it is important that the perforations in the sheath should be of such a size and number that while they allow sufficient liquid to pass through to the cake to effect the desired treatment, they do not greatly reduce the resistance of the sheath to the passage of the liquid.

In the accompanying drawing Figure 1 is a cross-section of an apparatus suitable for treating a number of cakes, Figure 2 is an outside elevation of the holder with its perforations, Figure 3 is an outside elevation of the rubber sheath showing the perforations therein and Figure 4 is a cross-section illustrating apparatus suitable for treating a single cake.

Referring to Figure 1, the apparatus comprises a clamp screw 1 provided with a clamp 2 which may be tightened as desired by means of the nut 3. The holder 4 surrounds the clamp screw 1 and is provided with a number of perforations 5 (Figure 2); the holder is fitted by means not shown to a supply of the desired treating liquid. Between the cakes 6 and the holder 4 there is provided a soft rubber sheath 7 which is provided with perforations 8 (Figure 3), the number and size of the perforations 8 being much less than those of the perforations 5 in the holder.

The sheath is maintained in position by the plate 9.

In Figure 4 an assembly is shown which holds only one cake. The reference numbers refer to like parts to those shown in Figures 1, 2 and 3.

What I claim is:

1. A method of treating a cake of artificial thread with liquids which comprises inserting in the cake a soft, flexible perforated sheath of elastic material, which sheath offers substantial resistance to the passage of liquid therethrough and supplying a treating liquid at the surfaces of the sheath remote from the cake at such a pressure that said liquid is forced through the perforations in the sheath and thence to and through the cake and the sheath is pressed against the cake to prevent the formation of creases in the cake.

2. A method of treating cakes of artificial threads with liquids which comprises assembling a plurality of said cakes on a central holder, providing between the holder and the cakes a soft, flexible perforated sheath of elastic material, which sheath offers substantial resistance to the passage of liquid therethrough and supplying a treating liquid at the surfaces of the sheath remote from the cakes at such a pressure that said liquid is forced through the perforations in the

sheath and thence to and through the cakes and the sheath is pressed against the cakes to prevent the formation of creases in the cakes.

3. Apparatus for the liquid treatment of cakes of artificial thread comprising in combination a tubular perforated holder and a soft permeable sheath of elastic material such as rubber, surrounding said holder, the size and number of the perforations in the said sheath being considerably less than the size and number of the perforations in the holder, so that the sheath offers substantial resistance to the passage of liquid supplied thereto under pressure and is pressed against the cake to prevent the formation of creases in the cake.

4. In a method of treating a cake of artificial thread with liquids the steps comprising inserting in the cake a soft flexible perforated sheath of elastic material which offers substantial resistance to the passage of liquid therethrough and supplying a treating liquid at the surfaces of the sheath remote from the cake at such a pressure that the sheath is held pressed against the cake and said liquid is forced through the perforations in the sheath and thence to and through the cake to prevent the formation of creases in the cake.

DESIRÉ C. F. DEVOS.
